UNITED STATES PATENT OFFICE.

NELSON WILBER AND WILLIAM FRITZE, OF DREWSEY, OREGON.

POSTHOLE AUGER.

1,411,395.

Specification of Letters Patent.

Patented Apr. 4, 1922.

Application filed July 27, 1921. Serial No. 487,878.

To all whom it may concern:

Be it known that we, NELSON WILBER and WILLIAM FRITZE, citizens of the United States, residing at Drewsey, in the county 5 of Harney and State of Oregon, have invented certain new and useful Improvements in Posthole Augers, of which the following is a specification, reference being had to the accompanying drawings.

10 This invention relates to certain improvements in post-hole augers and it is an object of the invention to provide a device of this general character embodying novel and improved means whereby the same may be ad- 15 justed or set to bore holes of different diam- eters in accordance with the necessities of practice.

Another object of the invention is to pro- 20 vide a novel and improved device of this general character so constructed that it will bore in substantially any soil and which includes blades provided with points or bits operating to loosen the gravel so that it will pass upwardly between the blades and 25 wherein the blades are provided with cutting edges to sever roots or the like of reasonable size, such as hazel brush or sage brush as may be encountered during a working operation.

30 Another object of the invention is to pro- vide a novel and improved device of this general character which, in addition to being particularly adapted for use in boring a post- 35 hole or the like, may be employed to advan- tage for cleaning out holes which are too small or too deep for an ordinary shovel.

The invention consists in the details of construction and in the combination and arrangement of the several parts of our im- 40 proved post-hole auger whereby certain im- portant advantages are attained and the de- vice rendered simpler, less expensive and otherwise more convenient and advan- tageous for use, as will be hereinafter more 45 fully set forth.

The novel features of our invention will hereinafter be definitely claimed.

In order that our invention may be the better understood, we will now proceed to 50 describe the same with reference to the accom- companying drawings, wherein:

Figure 1 is a view in elevation, with 55 portions broken away, of an auger con- structed in accordance with an embodiment of our invention;

Figure 2 is an enlarged sectional view

taken substantially on the line 2—2 of Figure 1;

Figure 3 is an enlarged sectional view taken substantially on the line 3—3 of Figure 1; and

Figure 4 is an enlarged sectional view taken substantially on the line 4—4 of Figure 1.

As disclosed in the accompanying draw- 65 ings, 1 denotes an elongated member or rod herein disclosed as angular in cross section and which has secured to its lower end portion a cross head 2. The cross head 2 at its opposite end portions is provided there- 70 through with the openings 3, said openings having their axes converging in a direction outwardly of the head 2 with the walls there- of convex in cross section.

Slidably disposed through the openings 75 3 are the rods 4 converging at all times in a direction toward the head 2 and which terminate outwardly of the head 2 in the laterally disposed extensions 4^a. The ex- 80 tensions 4^a are continued by the forwardly 85 directed arms 5 which are riveted or other- wise fixed to the blades B. The opposite end portions of the rods 4 are inwardly inclined, as at 4^b, with the extremities of said inclined portions pivotally engaged, as at 6, with 90 the opposite end portions of a cross member 7. The cross member 7 is slidably mounted upon the rod or member 1 and the move- 95 ment of said member 7 along the member or rod 1 in a direction away from the cross head 2 is limited by a pin 8 or the like in- 100 sertible through one of a series of longitudinally spaced openings 9 disposed through the rod or member 1.

Each of the blades B is of a spoon for- 95 mation with its concave face inwardly dis- posed and the lower extremity of said blade is provided with a point 10 and a heel 11. The blade B has its forward longitudinal margin entirely therealong formed into a 100 knife or cutting edge.

The greater the extent of movement of the cross member 7 inwardly of the rod or member 1, the greater the separation of the blades B and the diameter of the bore of 105 the opening and vice versa.

When the device is set for a working oper- 110 ation, the blades B automatically separate to the desired extent due to the separation of the rods 4 as the cross head 2 moves down- wardly thereof. As the rod or member 1 is rotated, the blades B effectively cut the earth

while the cutting or knife edges of said blades permit the same to readily penetrate roots or like obstructions. During this operation, the point 10 loosens the earth while 5 the heel 11 serves to elevate the loosened earth between the blades B and thereby prevent the points 10 from clogging. When the space between the blades is substantially filled by loosened earth or the like, pull is 10 imposed upon the member or rod 1 whereupon the blades B will automatically grip such loosened earth or the like and press the same between the blades so that said loosened material can be readily and conveniently 15 drawn out of the hole. By forcing down on the member or rod 1 while the points 10 of the blades B are on the ground, said blades will have separating movement and thus release the material held there- 20 between.

While our improved device is particularly adapted for use in the boring of post-holes or the like, it can also be employed to advantage in the cleaning out of holes when 25 rock or the like has been loosened by a digging bar and when such holes are too small or too deep for the usual shovel.

To facilitate the operation of the device, we have slidably engaged with the outer or 30 upper end portion of the rod or member 1 a sleeve 12 provided with the oppositely directed handle members 14. The sleeve 12 is held in desired position upon the member or rod 1 by a pin 15 which is adapted 35 to be inserted through the sleeve 12 and one of the series of longitudinally spaced openings 16 provided in the member or rod 1.

From the foregoing description it is thought to be obvious that a post-hole auger 40 constructed in accordance with our invention is particularly well adapted for use by reason of the convenience and facility with which it may be assembled and operated, and it will also be obvious that our invention 45 is susceptible of some change and modifications without departing from the principles and spirit thereof, and for this reason we do not wish to be understood as limiting ourselves to the precise arrangement and formation of the several parts herein shown in carrying out our invention in practice except as hereinafter claimed.

We claim:

1. An auger of the class described comprising an elongated member, a cross member slidably engaged therewith, rods pivotally engaged with said slidable member, a cross head carried by said first named member adjacent an end thereof, said rods being slidably disposed through said cross head, and blades carried by the rods outwardly of the cross head.

2. An auger of the class described com-

prising an elongated member, a cross member slidably engaged therewith, rods pivotally engaged with said slidable member, a cross head carried by said first named member adjacent an end thereof, said rods being slidably disposed through said cross head, blades carried by the rods outwardly of the cross head, and means for limiting the movement of the cross member along the first named member in a direction away from the cross head. 75

3. An auger of the class described comprising an elongated member, a cross member slidably engaged therewith, rods pivotally engaged with said slidable member, a cross head carried by said first named member adjacent an end thereof, said rods being slidably disposed through said cross head, and blades carried by the rods outwardly of the cross head, said blades being of substantial spoon formation with their 80 convex faces opposed.

4. An auger of the class described comprising an elongated member, a cross member slidably engaged therewith, rods pivotally engaged with said slidable member, a cross head carried by said first named member adjacent an end thereof, said rods being slidably disposed through said cross head, and blades carried by the rods outwardly of the cross head, said blades being of substantial spoon formation with their 85 convex faces opposed, the outer end portion of each of said blades being provided with an inwardly directed point. 90

5. An auger of the class described comprising an elongated member, a cross member slidably engaged therewith, rods pivotally engaged with said slidable member, a cross head carried by said first named member adjacent an end thereof, said rods being 95 slidably disposed through said cross head, blades carried by the rods outwardly of the cross head, said blades being of substantial spoon formation with their convex faces opposed, the outer end portion of each of 100 said blades being provided with an inwardly directed point, and an elevating heel positioned adjacent the point. 105

6. An auger of the class described comprising an elongated member, a cross member slidably engaged therewith, rods pivotally engaged with said slidable member, a cross head carried by said first named member adjacent an end thereof, said rods being 110 slidably disposed through said cross head, and blades carried by the rods outwardly of the cross head, said rods converging in a direction toward the cross head. 115

In testimony whereof we hereunto affix 120 our signatures.

NELSON WILBER.
WILLIAM FRITZE.
